(57) **CLAIM**

The ornamental design for a pet carrier, as shown and described.

DESCRIPTION

FIG. 1 is a front perspective view of the pet carrier;

FIG. 2 is a front view of the pet carrier;

FIG. 3 is a rear view of the pet carrier;

FIG. 4 is a left side view of the pet carrier;

FIG. 5 is a right side view of the pet carrier;

FIG. 6 is a top view of the pet carrier; and,

FIG. 7 is a bottom view of the pet carrier.

The broken lines showing in FIGS. 1-7 are included for the purpose of illustrating portions of the pet carrier that form no part of the claimed design.
